UNITED STATES PATENT OFFICE

93,810

DESIGN FOR A DISPENSING DEVICE FOR LIQUIDS

Rudolph Bernhardt, Chicago, Ill.

Application June 29, 1934, Serial No. 52,397

Term of patent 3½ years

To all whom it may concern:

Be it known that I, RUDOLPH BERNHARDT, a citizen of the United States and resident of Chicago, in the county of Cook, and State of Illinois, have invented a new, original, and ornamental Design for Dispensing Devices for Liquids, of which the following is a specification, reference being had to the accompanying drawing, forming part thereof.

Figure 1 is a perspective view looking down-

wardly on the device, as it would normally be positioned; and

Figure 2 is a perspective view of the device as seen at another angle or looking upwardly toward the same.

I claim:

The ornamental design for a dispensing device for liquids as shown and described.

RUDOLPH BERNHARDT.
